UNITED STATES PATENT OFFICE.

MANUEL CARRANZA, OF HAVANA, CUBA.

DESIGN FOR A SPOON.

SPECIFICATION forming part of Design No. 21,258, dated December 22, 1891.

Application filed November 18, 1891. Serial No. 412,326. Term of patent 7 years.

To all whom it may concern:

Be it known that I, MANUEL CARRANZA, a citizen of Mexico, residing at Havana, Cuba, have invented and produced a new and original Design for a Spoon, of which the following is a specification, reference being had to the accompanying drawing, forming part thereof, which represents a spoon decorated in accordance with my design.

10 The principal feature of the design consists in the decoration of the bowl of the spoon, which decoration consists of a simulation of the harbor of Havana and its castle El Morro, the words "El Morro" being artistically drawn upon the bowl. The handle of the spoon at its upper end and at the upper portion of its sides upon the front face is decorated with leaf-like scrolls and with letters of artistic

formation, arranged one above the other and reading "Habana," the word "Habana" appearing as within a panel, owing to rib-like figures located at the sides of the spoon-handle beneath the leaf-like scrolls. The panel appears as connected with a column, the column losing itself in the bowl.

20 Although I have alluded to the words "El Morro" and "Habana" as drawn upon the spoon, I do not claim them as a portion of the design.

25 I claim—

30 The design for a spoon, substantially as herein shown and described.

MANUEL CARRANZA.
